ATION OF NEW JERSEY

COUNTERBALANCING DEVICE

Application filed July 25, 1930. Serial No. 470,714.

This invention relates to improvements in counterbalancing devices, being particularly directed to an improved spring balancing hinge.

5 The primary object of the invention is to provide a hinge or like device which is counter balanced when it is moved in either direction to open or in a direction to close the particular element which is attached to the hinge.

A further object of the invention is to provide a hinge which is counter balanced in both of the movements of direction by a single spring member.

15 Other objects, novel features of construction and improved results of the invention will appear from the following description and accompanying drawings.

In the drawings:

20 Figure 1 is a view in side elevation of the improved device showing an application of the same to a stove, a portion of the view being in vertical section.

25 Fig. 2 is a view in side elevation of the improved device, one position of the hinge being shown in full lines and another position being shown in dotted lines.

30 The present invention has been conceived for the purpose of counter-balancing a hinge carrying a hood or cover for the cooking top portion of a gas range, but it will be readily apparent that the principle of the invention can be applied to hinges used for other purposes without departing from the spirit of 35 the invention, and that minor differences of construction over that shown in the accompanying drawings can be readily made and still be within the confines of the present invention, as set forth in the appended claims.

40 The present invention has been conceived for the purpose of providing a simple, inexpensive yet durable and convenient device for use with raising and lowering or opening and closing elements, where it is either necessary or desirable to have the elements spring balanced either for ease of operation or for the purpose of preventing the elements from dropping or slamming when they are moved from a raised to a lowered or from an open 45 to a shut position.

Reference being had to the drawings which illustrate one use to which the invention could be put, 3 designates the frame, which is usually of angle-iron surrounding the cooking top portions of a gas range, while 4 designates a hood or cover for covering and concealing the cooking top portion of the range. This hood or cover is pivotally supported upon the stove frame 3, by one or more 50 hinges, such as illustrated at 5. This hinge 55 is pivotally mounted, as at 6, on the stove frame and has an upwardly extending arm 7, to which is fastened a portion 8 of the hood and also provided with a downwardly extending arm 9, which extends through opening 10 in the stove frame to terminate at a point beneath the same.

55 Suitably attached, as at the points 11, to the stove frame and suspended in a position beneath the same is a bracket 12 of the configuration illustrated in the drawings, although the particular configuration is not essential to the present invention. The bracket is fastened at two places for the purpose of making it rigid, but as will be evident after a further reading of the description, this bracket could be in the form of one 60 depending arm only, provided the same is sufficiently strong.

65 A coil spring 13 has its one end attached, as at 14, to the lower end of the dependent arm 9 of the hinge, while its other end is attached as at 15 to the adjustable screw or turn buckle 16, carried by the bracket 12.

70 With the parts in the positions shown in Figure 1, where the hood is in its lowered position, the turn-buckle 16 is so adjusted that the coil spring is under tension, thus exerting a pull upon the hinge arm 9 in a direction indicated in this figure of the drawings 75 by arrow, with the result that as the hood or cover is manipulated by its handle 17 to assume a lowered position, this spring has a tendency to counter balance the weight of the hood or cover to prevent it from slamming 80 downwardly to its closed position.

85 When the hood or cover is lifted, and is approximately midway between its raised and lowered positions, the hinge and spring assume the positions illustrated in full line 90

in Figure 2 of the drawings where it will be seen that the depending arm 9 of the hinge and the spring 13 have moved towards the right, with the result that the spring is in a normal position and is exerting no tension whatsoever upon the hinge arm 9. This might be termed the neutral position of the hinge.

When the cover or hood has been completely raised, the parts assume the position illustrated in dotted lines in Fig. 2 of the drawings, where it will be seen that the hinge arm 7 is paralleling the upper surface of the angle-arm frame of the stove, while the hinge arm 9 is paralleling the under surface of the angle-iron frame of the stove. The spring 13 has moved to the right to a position beyond that which it assumed when the parts were in their neutral positions with the result that the spring has come into contact with what we have termed a compensating member 17, which in reality is a rigid element carried by the frame 12 and positioned in the path of travel of the coil spring.

The result of the contact between the coil spring 13 and the compensating member 17 is to cause a distortion of the spring as clearly indicated in Fig. 2 of the drawings, which distortion puts the spring under tension and causes it to pull downwardly upon the hinge arm 9 in the direction indicated by arrow. This downward pull upon the hinge arm 9 gives a resultant uplift upon the hinge arm 7 and prevents the hood or cover 8 from slamming upon the stove frame 3, when the cover is moved into its lifted position.

From the construction described, it will be seen that we have provided a hinge which is counter-balanced in both directions of movement by a single spring and that the device although simple in construction is highly efficient in operation.

A device of the character herein described is very desirable when raising or lowering, or opening or closing a door, cover or some similar device of considerable weight or considerable size, as it will prevent the element from striking with full weight when assuming either of its extreme positions. The device is particularly advantageous when used on a stove wherein the parts are enameled, because sudden jars or slamming will cause a cracking of the enamel and in opening and closing the parts or doors of a stove the operator oftentimes releases the handle of the door or like element before the same has reached either its complete open or closed position.

Attention is directed to the fact that the compensating member need not necessarily be of the particular shape illustrated in the drawings; that varying designs or types of spring could be utilized; that the bracket could readily be formed in other shapes than that illustrated; that the hinge could be

made in different shapes; and that the device could be applied to other constructions than that illustrated in the drawings, but that these various constructional changes would still not depart from the spirit of the invention wherein a counter balance arrangement is provided in the medium of a single spring.

Having thus described our invention, what we claim and desire to secure by Letters Patent is:

1. A counter-balancing device for a hinge comprising a coil spring, said coil spring being under tension when the hinge is in one extreme position, and means in the path of travel of said spring to distort the spring to put it under tension when the hinge is moved to its other extreme position.

2. In combination with a pivotally mounted hinge member, arms extending to each side of the said pivotally mounted hinge member, a coil spring connected to one hinge arm and exerting a tension thereupon when the hinge is in one extreme position, and means in the path of travel of said spring to distort the same and cause a tension upon the hinge arm when the hinge is moved to its other extreme position.

3. In combination with a pivotally mounted hinge member having arms extending to either side of the pivotal support of said member, a support, a coil spring having connection with said support and one of said hinge member arms, a compensating member carried by said support in the path of travel of said spring, and said spring causing a tension upon the movement of the hinge member in either direction.

4. In combination with a hinge member, a coil spring connected thereto, a bracket, said spring having adjustable connection with said bracket, a member positioned in the path of travel of said spring, and said spring adapted to cause a tension upon the hinge member upon movement with the hinge member in either direction.

5. An improved device for supporting doors or the like, comprising a pivotally mounted hinge member having a pair of arms, one of which carries said door, a spring attached to the other hinge arm and to a fixed anchor, said spring exerting a tension upon said hinge arm tending to retard the closing of the door when the door is moved to a closed position, a member positioned in the path of travel of said spring when the hinge is swung to move the door to an open position, and said spring being distorted by said member to cause a tension upon the hinge arm tending to retard the opening of the door when the door is moved to an open position, for the purpose described.

6. An improved device comprising a stove frame, a hinge member pivotally supported thereupon and carrying a cover, for the be-

- fore said stove frame, said hinge member having an extending portion to which is attached a spring, a bracket attached to said stove frame to which said spring is anchored, 5 a compensating member carried by said bracket in the path of travel of said spring and said spring adapted to cause a tension upon the hinge member to retard the movement of the hinge in either direction.
- 10 7. A counter-balancing device for a pivotally mounted member, comprising a spring, said spring retarding the movement of said member in either of its directions of movement around its pivot as said member approaches the end of its travel.
- 15 8. A counter-balancing device for a hinge or the like comprising, a spring, said spring retarding the movement of said hinge when the hinge is moved to either open or closed 20 position.
- 25 9. In combination with a hinge member or the like, a spring connected thereto and movable therewith, and said spring in its movement being put under tension, relieved of its tension and then again put under tension; 25 for the purpose described.
- 30 10. A counter-balancing device for a hinge or the like comprising a spring, said spring under tension when the hinge is in one extreme position and movable with the hinge to its other extreme position, and when in said other extreme position said spring under tension and exerting a force upon said hinge in a direction at right angles to the tension originally exerted upon the hinge.
- 35 11. A counter-balancing device for a pivotally mounted member movable in a circular path, comprising a spring connected to and movable with said member, said spring exerting a pull upon said member when the member is at one end of its path of travel and exerting a pull in a different direction when the member is at the opposite end of its 40 path of travel.
- 45 12. A counter-balancing device for a hinge or the like comprising a spring, said spring being under tension when the hinge is in one extreme position and moved in a direction transverse its axis when the hinge is moved to its other extreme position, the tension of 50 said spring released during the movement of the hinge from one position to the other, and means in the path of travel of the spring to put it again under tension as the hinge approaches its said other extreme position.

55 In testimony whereof we hereunto affix our signatures.
